UNITED STATES PATENT OFFICE

114,602

DESIGN FOR A WEDDING GOWN

Murray J. Shapiro, New York, N. Y.

Application March 25, 1939, Serial No. 83,840

Term of patent 3½ years

To all whom it may concern:

Be it known that I, Murray J. Shapiro, a citizen of the United States, residing in New York city, in the county of New York and State of New York, have invented a new, original, and ornamental Design for a Wedding Gown, of which the following is a specification, reference being had to the accompanying drawing, forming part thereof.

Fig. 1 is a front view of a wedding gown showing my design, and

Fig. 2 is the rear view thereof.

I claim:

The ornamental design for a wedding gown, substantially as shown.

MURRAY J. SHAPIRO.
